(57) **CLAIM**

The ornamental design for a recreational pad for spraying water, as shown and described.

DESCRIPTION

FIG. 1 is a perspective view showing our new design;

FIG. 2 is a front side elevation view thereof;

FIG. 3 is a rear side elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines, including the inflatable basketball hoop, illustrate portions of the recreational pad for spraying water that form no part of the claimed design.
